Patented Nov. 6, 1962

194,010

GAS BURNER

Walter Glen Klepzig, Abbeville, Miss., assignor to Chambers Corporation, a corporation of Indiana

Filed Feb. 21, 1962, Ser. No. 68,918

Term of patent 14 years

(Cl. D81—10)

FIG. 2 is a side elevational view thereof;

FIG. 3 is an end elevational view thereof;

FIG. 4 is an end elevational view, taken from the opposite end of FIG. 3; and

FIG. 5 is a bottom plan view thereof.

I claim:

The ornamental design for a gas burner substantially as shown.
